Primary Examiner — Richard Kearney*Assistant Examiner* — Anthony Vincent Rotolo(74) *Attorney, Agent, or Firm* — CALDERON SAFRAN & WRIGHT P.C.(57) **CLAIM**

The ornamental design for a taillight for a vehicle, as shown and described.

DESCRIPTION

FIG. 1 is a front view of a taillight for a vehicle showing my new design;

FIG. 2 is a left rear perspective view thereof;

FIG. 3 is a left side view thereof; and,

FIG. 4 is a top view thereof.

The elements shown in broken line illustrate environmental structure that forms no part of the claimed design.

The vertical dot-dash line within the environmental structure is a break line, which forms no part of the claimed design. The surfaces illustrated using black regions form the claimed design: the color black, itself, is not claimed; the color black is used to show a contrast in material appearance.
